UNITED STATES PATENT OFFICE.

GEORG ULLRICH, OF MAGDEBURG, GERMANY, ASSIGNOR TO FRIED. KRUPP AKTIEN-
GESELLSCHAFT, GRUSONWERK, OF MAGDEBURG-BUCKAU, GERMANY.

MAGNETIC SEPARATOR.

1,130,648.

Specification of Letters Patent.

Patented Mar. 2, 1915.

Application filed November 25, 1913. Serial No. 302,945.

To all whom it may concern:

Be it known that I, GEORG ULLRICH, a subject of the King of Bavaria, and resident of Magdeburg, German Empire, have invented certain new and useful Improvements Relating to Magnetic Separators, of which the following is a specification.

This invention relates to magnetic separators for simultaneously treating magnetic materials of different kinds or grades, and has reference to separators of the kind in which the material to be treated travels across the magnetic field in the same direction, relatively to the co-operating magnet pole, as the direction of travel of the surface to which the magnetic or magnetizable particles are attracted and adhere while in the magnetic field. Hitherto in separators of this kind,—for instance those in which a co-axial assemblage of disks rotates about a horizontal axis above a magnet pole between which and the disk-peripheries the material travels transversely with respect to the said axis,—the material during the advancing portion of its travel across the magnetic field traverses a region of increasing magnetic strength, and after passing the mid-point of the field traverses, during the retreating portion of its travel, a region of decreasing magnetic strength. Although such separators can be used for treating magnetic materials of different kinds or different degrees of permeability, the particles separated in any one zone of the magnetic field, and subsequently removed therefrom, are not all of the same permeability but comprise a mixture of particles differing in permeability.

The chief object of the present invention is to provide an improved form of separator of the kind above referred to so that a much sharper division can be obtained between the several kinds or grades of particles than has hitherto been possible with such separators.

According to the present invention the magnetic separator is so constructed and arranged that the material to be treated traverses a field of graduated or "stepped" magnetic strength, and has its magnetic or magnetizable constituents attracted to and carried upon the traveling surface of attraction in superposed strata or layers of graduated permeability, from which surface the said strata or layers subsequently fall or are re-

moved in the inverse order of their attraction, and collected separately.

In order that the invention may be clearly understood and readily carried into effect, I shall now describe the same more fully with reference to the accompanying drawing which illustrate in Figure 1, a cross section of one constructional form of the relevant parts of a separator adapted to operate in accordance with the invention; Figs. 2 and 3 are similar views to Fig. 1, but in smaller scale, and showing adjusting means for the lamellæ of the lower pole; Fig. 4 is similar to Fig. 2 but showing adjusting means for the lower pole when made in one piece; Fig. 5 is also a cross section with both upper and lower pole pieces adjustable, but only the upper one made up of lamellæ; Fig. 6 is of the same character as Fig. 2 but has a flat collecting band; Fig. 7 shows the upper pole as a horizontally rotating ring and Fig. 8 shows the lamelle of the upper pole considerably offset relative to the lower pole.

The separator comprises an upper magnet pole *a*, a rotary cylindrical attracting surface of which *b* is a fragment, and a lower magnet pole *c*. The lower pole *c* is graduated or stepped for the purpose of dividing the magnetic field between the two poles into zones of different magnetic strength; in the drawing three pole elements *d* are shown, dividing the field into three zones, the strengths of which increase in the direction in which the material to be treated travels. The zones can be fixed or variable, the latter condition being attained either by means of interchangeable magnet pole pieces, *m* Fig. 4, or, as illustrated, in Figs. 1, 2, 3, 6 and 7 by dividing the lower pole into lamellæ *d* or pole elements adjustable independently of one another by means of set screws *s*. Obviously the "stepped" magnetic field could be obtained by interchangeability as with pole piece 1, Fig. 3 or 100 laminate-adjustment of the upper pole lamellæ *n*, Fig. 5 instead of, or in addition to, providing for such manipulation of the lower pole.

The material to be separated is conducted into the magnetic field in the direction indicated by the arrow *x* and is transferred to the cylinder *b* in a number of superposed strata corresponding to the number of the pole elements *d*. The non-magnetic material 110

falls behind the pole *c* into a chute *f*. The magnetic material is carried over and beyond this chute by the cylinder *b*, and the several kinds or grades of magnetic material then fall from the cylinder in the reverse order to their attraction by it, that is to say, the lowermost and least magnetic layer falls first, and so on; the several kinds or grades fall separately down the chutes *g*, 10 *h*, *i*, and are collected separately.

In order to distribute the falling of the material over a long path, an extension *k* projecting beyond the edge of the lower pole can be provided on the upper pole as shown. 15 If this extension is composed of lamellæ *q*, Fig. 8, adjustable independently of each other in an arm *k*², the falling of the several kinds or grades of magnetic material can be exactly regulated.

Instead of employing the surface of a rotary hollow cylinder to convey the attracted magnetic material, any other appropriate conveying device may be employed; the principle underlying the invention may for 20 instance be adapted in the case of separators in which the conveying device is a traveling band *o*, see Fig. 6, or a ring *p*, rotating around a vertical axis.

With reference to the graduated or "stepped" magnetic field, it may be remarked that hitherto the division of the magnetic field into zones of magnetic strength has usually only been adopted in the case of separators in which the direction 30 of travel of the material under treatment, intersects the direction of travel of the conveying surface; in such cases however the width of track of the material to be treated is generally limited because for the greater 35 part of this width the magnetic material that has been attracted during travel of the conveying surface over the first part of the width, has to be carried over material that has still to undergo attraction. The adoption of zone formation in separators of the 40

kind to which the present invention relates does not, however, present the above mentioned defect, namely limitation of width of the supply track. The present device makes possible a sharp division of the several kinds or grades of magnetic material, by separating out the kinds or grades in the magnetic field as hereinbefore described. Consequently the present invention presents a two-fold advantage. 50 55

Claims:

1. A magnetic separator of the kind set forth, comprising upper and lower stationary poles, a traveling member moving through the field gap in the direction of feed of material, and means for feeding the material to be separated into the gap, means for increasing the strength of the field in steps and then decreasing the same in the same direction of feed, and means for separately collecting the grades progressively released from the traveling member. 60 65

2. A magnetic separator of the kind set forth, comprising upper and lower stationary poles, a traveling member moving through the field gap, and means for feeding the material to be separated into the gap beneath and in the same direction as the traveling surface of said member moves across the magnetic field, means for dividing said 70 field into sharply defined adjustable zones of strength increasing in the direction of feed, said zones extending transversely of the direction of feed, means for subsequently decreasing the field strength in the same direction, and means for separately collecting the different grades of material as released from the traveling member. 75 80 85

The foregoing specification signed at Magdeburg this 4th day of November, 1913. 85
